United States Patent Office

Des. 194,859
Patented Mar. 19, 1963

194,859

LETTER OPENER

Donald F. Haldeman and Clifford A. Stone, both of
700 Tower Bldg., Seattle, Wash.

Filed Nov. 17, 1961, Ser. No. 67,582

Term of patent 14 years

(Cl. D74—1)

FIG. 1

FIG. 2

FIG. 3

FIG. 4

FIG. 5

FIG. 6

FIG. 1 is a top plan view of a letter opener showing our new design;

FIG. 2 is a bottom plan view thereof rotated end for end at an angle of 90°;

FIG. 3 is an end elevational view as seen from the right of FIG. 1;

FIG. 4 is an end elevational view as seen from the left of FIG. 1;

FIG. 5 is an edge view as seen from the bottom of FIG. 1; and

FIG. 6 is an edge view thereof as seen from the top of FIG. 2.

We claim:

The ornamental design for a letter opener, as shown.
